UNITED STATES PATENT OFFICE.

THEODORE H. JOHNSON, OF WASHINGTON, DISTRICT OF COLUMBIA.

ANTISLIPPING SHOE.

1,120,059.

Specification of Letters Patent.

Patented Dec. 8, 1914.

Application filed February 21, 1913. Serial No. 750,029.

To all whom it may concern:

Be it known that I, THEODORE H. JOHNSON, a citizen of the United States, residing at Washington, District of Columbia, have 5 invented certain new and useful Improvements in Antislipping Shoes; and I do hereby declare the following to be a full, clear, and exact description of the invention, such as will enable others skilled in the art to 10 which it appertains to make and use the same.

The present invention is directed to anti-slipping shoes for attachment to horses' hoofs which have been shod.

15 The invention has for its object to so construct an article of this character that the same may be readily attached to or detached from a horses' hoof.

20 A further object of the invention is to so construct an article of this type that the same can be quickly attached to the shod hoofs of a horse so as to prevent the animal from slipping when traveling over wet or ice covered pavements.

25 With these and other objects in view, this invention resides in the novel features of construction, formation, combination, and arrangement of parts to be hereinafter more fully described, claimed and illustrated in 30 the accompanying drawing, in which:—

Figure 1 is a perspective view of the device showing the same attached to the hoof. Fig. 2 is a similar view showing the same detached. Fig. 3 is a transverse sectional view.

35 The device consists of a body 1 which is formed from a single piece of suitable metal and comprises a base plate 2, said plate being formed so as to conform to the usual shape of the horse shoe 3.

40 The inner edge of the base plate 2 terminates in a vertical flange 4, which corresponds to the curvature of the base plate 2. The ends of the flange 4 are connected by a plate 5 on top of said flange, which 45 strengthens the device, and provides a support for the hoof frog.

45 Formed integral with the forward end of the base plate 2 is an ear 7, which is inwardly inclined so as to rest against the 50 front of the hoof. The ear 7 terminates in a tongue 8, the extreme upper end of which being reversely bent so as to provide a loop 9, the purpose of which will appear later.

55 Arranged diametrically opposite and formed integral with the side edges of the

base plate 2 are ears 10 which engage the sides of the hoof.

To one of the ears 10 is connected the lower end of the strap 11, and to the other ear 10 is connected the lower end of a strap 12, 60 which has its upper end passed through the loop 9, and is provided with a buckle 13 which is engaged by the strap 11, and when engaged thus said straps serve to firmly hold the device upon the hoof. 65

By providing the ears 10 channels 14 are produced for snugly receiving the rear ends of the shoe 3, the forward end of which being received in a channel 15 formed by the ear 7 and flange 4. It will be noted that 70 when the device is in place upon the hoof the inner edge of the shoe 3 will rest against the flange 4, and that the toe and heels of said shoe will engage the channels 15 and 14, respectively, thereby preventing relative movement of the shoe 3 and the device. 75

The base plate 2 is provided with a toe calk 16 and heel calks 17, which prevent slippage of the device, said calks being 80 formed integral with the base plate 2.

From the foregoing description it will be seen that an anti-slipping shoe has been provided which can be conveniently attached to a horse's hoof when necessary, and one which 85 may be manufactured at a minimum cost. 85

What is claimed is:—

An anti-slipping shoe of the class described comprising a body, formed from a single piece of metal and consisting of a base plate, a vertical flange formed integral 90 with the inner edge of the base plate, a cross rest on top of said flange and connecting the ends thereof affording a support for the foot, ears formed integral with the side edges and front edge of the base plate, said ears being spaced from the flange to produce shoe receiving channels for receiving the toe and heels of the shoe, one of said ears terminating in a tongue having a loop 95 formed upon its upper end, and means carried by the first named ears and engaging the loop to hold the device upon the hoof of the animal. 100

In testimony whereof, I affix my signature, in the presence of two witnesses.

THEODORE H. JOHNSON.
